UNITED STATES PATENT OFFICE.

PETER CUNNEEN, OF NEW ROCHELLE, NEW YORK.

DISH RACK.

Application filed October 14, 1921. Serial No. 507,628.

To all whom it may concern:

Be it known that I, PETER CUNNEEN, a citizen of the United States, residing at New Rochelle, county of Westchester, State of New York, have invented certain new and useful Improvements in Dish Racks, of which the following is a specification.

My invention relates to portable devices for supporting dishes while being washed and rinsed, and is a modification of the construction disclosed in an application for a similar device filed by me July 23, 1921, Serial No. 487,033.

More specifically, my invention contemplates a different form of adjustment of the dish supporting members, as well as the provision of separate means for supporting knives, forks and spoons while being washed and rinsed, as hereinafter more definitely will be pointed out, reference being had to the accompanying drawings, in which:—

Figure 1 is a side elevation of my improved device, the same being shown in its closed position.

Figure 2 is a top plan view of the same, shown in the same position.

Figure 3 is an end elevation of the same, the supporting members being shown in dotted lines in open position.

Figure 4 is a detail perspective view, partly broken away, of one of the supporting members and the fork and spoon supporting rack, the latter shown in operative position.

Figure 5 is a detail top plan view of a portion of said rack, illustrating the manner of inserting one of the articles to be supported in one of the apertures therein.

Figure 6 is a detail perspective view of a portion of one of the supporting members, showing a different manner of supporting an article, such as a spoon.

Figure 7 is a detail perspective view showing the knife supporting rack in operative position.

Figure 8 is a transverse sectional view through the parts shown in Figure 7.

Figure 9 is a perspective view of my improved fork and spoon holder and my improved knife holder shown applied to the construction illustrated in my application Serial No. 487,033 hereinbefore referred to.

Figure 10 is a detail side elevation of the knife holder shown so applied.

Figure 11 is a transverse sectional view, taken on the line XI—XI of Figure 10.

Figure 12 is a detail transverse sectional

view taken through that portion of the frame supporting the fork and spoon holder, the latter being shown in its retracted position.

Similar numerals of reference denote corresponding parts in the several views.

Referring to said drawings, and more particularly to Figures 1 to 8, the reference numerals 1 denote transverse base bars, which may be formed of wood, or if desired, of any suitable metal, and which form the bottom supports for the device. Fixed to said bars 1, by suitable screws 2, are the brackets 3, formed with oppositely disposed ears or lugs 4, in which are pivoted the dish supporting frames, each of the latter comprising longitudinal top bars 5 and lower bars 6 connected by vertical end bars 7, all of which may be formed of wood, or, if desired, of any suitable metal. The bars 5 each are provided with a plurality of notches 8 extending substantially the length of the same, said notches, when the bars are properly positioned, facing towards each other, as shown. Pivoted to each of the brackets 3 at 9 are a pair of notched bars 10, the notches in the same being adapted to engage pins 11 projecting outwardly from the vertical bars 7, whereby to retain the dish supporting frames in any adjusted position from the vertical to the inclined dotted line positions shown in Figure 3, in a manner readily understood.

Mounted and vertically movable at the upper outside face of one of the dish supporting frames is a knife and spoon supporting rack, the same comprising end arms 12 passing loosely through suitable U-shaped staples 13 fixed in the outer faces of the upright members 7, said arms 12 being formed with hooks 14 at their lower ends to limit the normal upward movement of said rack, as clearly shown in Figure 4, and said arms being angled or notched at 15 to fit over the edge of the dish supporting frame, as shown. The longitudinal member 16 of said rack is formed in the shape of an inverted V, and is provided with a plurality of longitudinal apertures 17 in the apex of the same, each of said apertures at one end merging into a widened transverse portion 18, as clearly shown in Figures 4 and 5. This construction is provided for the purpose of permitting the insertion of the handle of a fork or spoon, when the same is turned parallel with the length of said member 16, said article when inserted being turned at a right angle to fit in the widened portion 18 of the aperture in

which it is inserted and being retained there-in against any but positive removal.

Mounted upon the other dish supporting frame 7 is a knife rack 19, the same being provided with a central vertical slot 20, through which passes a screw-bolt 21 fixed in the dish supporting frame and carrying a thumb-nut 22, as shown. Near the ends of said rack are upper hook members 23 and 10 lower hook members 24, which limit the movement of the rack at its ends in either direction. Said rack is provided with a series of narrow slots 25 in its upper edge, said slots merging into substantially circular apertures 26 at their lower ends, the bottoms of said circular apertures being slightly notched at 27 to receive the lower edges of the knives. As shown in Figure 7, when this rack is raised to its uppermost position, which may be done by loosening the thumb-nut 22, and raising the rack until the hooks 24 engage with the underside of the upper bar 5, and then tightening said thumb-nut, the knives may be inserted into 25 the slots 25 and will rest at their lower edges in the notches 27, their handles resting upon the opposite plate supporting frame, as clearly shown in Figure 7.

In utilizing my improved device when it is desired to wash and rinse dishes, the dish supporting frame may be adjusted to any position from the vertical to that shown in dotted lines in Figure 3, which latter will receive and support plates of large size, one of said plates being shown therein in dotted outline. For smaller plates, the notched bars 10 provide means for retaining the plate supporting means as close together as may be desired. In utilizing the rack 16, the same is raised to the position shown in Figure 4, whereupon the forks or spoons may be inserted therein, the manner of insertion being illustrated clearly in said figure, and the same will be positioned properly for the washing and rinsing operation. Similarly the knife rack 19 may be raised to operative position and knives disposed therein, as clearly illustrated in Figure 7. It will be understood that the device when filled with any articles to be washed is placed in a sink, and hot washing and rinsing water applied thereto as desired. When the operation is completed, the rack with its contents may be removed from the sink and placed in position to dry.

In Figure 6, I have shown the projections forming the notches 8 utilized as a rack for supporting knives, forks or spoons, the same being provided with notches 28 into which

the edges of the articles to be supported may 60 be inserted and which will retain them firmly in position during the washing and rinsing operation.

In Figures 9, 10, 11 and 12, I have illustrated my improved fork and spoon holder, 65 as well as the knife holder applied to the form of dish washer and drainer disclosed in my application for Letters Patent No. 487,033 hereinbefore referred to, and I wish it to be understood that said devices may be 70 applied to either construction, as may be desired. The application of said devices to the prior construction being apparent, further description of the same is deemed to be unnecessary.

Having thus described my invention, what I claim as new and desire to secure by Letters Patent, is:—

1. A dish rack, comprising means for supporting dishes in spaced relation, and a 80 rack vertically adjustable thereon into and out of operative position and adapted removably to receive and support therein spoons, forks and the like.

2. A dish rack, comprising means for supporting dishes in spaced relation, and a rack vertically adjustable thereon into and out of operative position, said rack comprising end arms hooked at their lower ends to engage said dish support to limit their upward movement and a longitudinal inverted V-shaped member apertured in its apex removably to receive and support therein spoons, forks and the like.

3. A dish rack, comprising means for supporting dishes in spaced relation, and a rack vertically adjustable thereon into and out of operative position, said rack comprising end arms hooked at their lower ends to engage said dish support to limit their upward movement and a longitudinal inverted V-shaped member formed with a plurality of longitudinal slots in its apex merging at one end into transverse slots, adapted removably to receive and support therein spoons, forks and the like.

4. A dish rack, comprising frames for supporting dishes in spaced relation, a rack vertically adjustable on one of said frames into and out of operative position and adapted removably to receive and support therein spoons, forks and the like, and a separate rack vertically adjustable on the other frame and slotted to receive and support the blades of the knives.

In testimony whereof, I heréunto affix my signature.

PETER CUNNEEN.
